TOBACCO PIPE

Edward H. McArdle, Elizabeth, N. J., assignor to
 William Demuth & Company, New York, N. Y.,
 a corporation of New York

Application March 15, 1933, Serial No. 660,829

1 Claim. (Cl. 131—12)

My invention relates to an improved tobacco pipe.

An object of the invention is to provide a pipe construction by which the smoke drawn into the smoker's mouth from the bowl through the bit will be relatively cool and substantially free of moisture, condensate and other undesirable constituents of the smoke.

Another object is to so construct and correlate the bowl and bit members that the latter may be used as a cigar or cigarette holder upon removal of the bit from its connection with the bowl.

Other objects of the invention will be apparent from the following description read in connection with the accompanying drawing.

I accomplish these objects by a peculiar interior construction of the bit and shank and by the provision of a fresh air inlet leading to the smoke passage within the pipe.

In the accompanying drawing, which is illustrative of one concrete form the invention may take, Fig. 1 is a longitudinal substantial central section of my improved pipe, with the several parts assembled in condition for use as a pipe; Fig. 2 is a transverse section on the line 2—2 of Fig. 1; Fig. 3 is a longitudinal section of the bit and shank when assembled for use as a cigar or cigarette holder, and Fig. 4 is a similar view of a modified form of shank.

Referring to the drawing 10 denotes the pipe bowl, 11 the shank and 12 the bit. These parts are made of any suitable material; the bowl usually being of briar root, meerschaum or clay, the shank of metal, hard rubber or synthetic resin, and the bit of hard rubber or synthetic resin.

The bowl 10 is desirably, although not necessarily, integral with a bowl stem 13 having a central smoke passage 14 terminating in a flare 15 at the end remote from the bowl.

The bowl 10 and shank 11 are removably connected together in any preferred manner. A desirable form of connection, as shown in Fig. 45 1 comprises a peripheral undercut groove 16 at the outer end of stem 13 engaged by the inner face of the shank end, which is of annular form. The engagement between the groove 16 and shank wall is in the nature of a friction fit, although other well known forms of air tight connection might be substituted therefor, such as screw threads or taper joints.

The shank 11 is provided with a chamber 17 with which the flared end 15 of the smoke passage 14 is in direct communication. The cham-

ber 17 is of greater size or capacity than the passage 14 and permits of expansion and preliminary cooling of the smoke. The wall of chamber 17 as it approaches the middle part of the shank 11 is tapered or contracted in gradual curvature to form the axial passage or orifice 18 which is preferably annular and terminates in the opening 18a.

An air hole or duct 19 is bored through the wall of the shank and leads from atmosphere to 10 a suitable point within the pipe, as for example to the passage 18. The hole 19, which is desirably of very small bore and serves to thoroughly mix indrawn air with smoke, extends radially of the shank axis, or differently expressed, ex- 15 tends substantially at right angles to the longitudinal axis of passage 18.

At the end of passage 18 opposite chamber 17, the shank 11 is provided with a second chamber 20 which may be of somewhat greater 20 capacity than the chamber 17. The wall of chamber 20 embraces an undercut peripheral groove 21 on the bit 12, thus uniting the bit and shank to each other. This connection, like the connection between the shank and bowl stem, 25 is in the nature of a friction fit although other appropriate forms of air tight connection might be used.

Countersunk into the wall of the smoke passage 22 in the bit 12 is part of a tube 23 bent at 30 its end 23a to be out of line with the passage 18. The tube 23 hinders the passage of moisture from the shank to the smoker's mouth.

The modified construction of Fig. 4 functions in substantially the same manner as the form 35 of Fig. 1. In Fig. 4, the interior passages and chambers have substantially the shape of a Venturi tube, the chambers 17a and 20a being tapered toward the connecting orifice 18b into which leads the air duct 19a.

When the pipe is in use, smoke is drawn from the bowl through the several chambers and passages into the smoker's mouth, the smoke flowing in a straight line through the chamber 17 although expanding therein to some extent. As 45 the smoke enters orifice 18 it is mixed with fresh air drawn in through duct 19, and the flow becomes turbulent and continues thus in chamber 20. The admixture of atmospheric air with the smoke and the turbulent flow in orifice 18 50 and chamber 20 result in causing excellent cooling of the smoke and the condensation and precipitation out of the smoke of the offensive constituents ordinarily contained in tobacco smoke. The upturned end of tube 23 prevents passage 55

of moisture into and through passage 22 and the smoke reaches the smoker's mouth in a relatively cool, dry and sweet condition.

By removal of the bowl 10 from the assembly, the shank and bit form a unit, Fig. 3, which serves effectively as a cigar or cigarette holder and, during smoking, offers all the advantageous effects obtained with the device when used as a pipe.

10 Should cleaning be necessary, it may be readily accomplished by separating the parts from one another and cleaning each in a manner well known in this art.

I claim:—

15 In a tobacco smoking device, the combination of a bowl and bored stem, the latter having a

peripheral groove at its end remote from the bowl, of a bored bit member having a peripheral groove at one end thereof, and a shank member having its opposite ends engaging said grooves, said shank containing a chamber decreasing in diameter from the bowl end of the shank to near the middle portion thereof, said shank also containing a chamber of substantially uniform diameter, said chambers being connected to each other, by a substantially annular orifice of restricted diameter the end of said orifice in the second mentioned chamber being square cornered, there being an air passage leading from atmosphere and opening directly into said orifice intermediate its ends. 10

EDWARD H. McARDLE. 15
